(57) **CLAIM**

The ornamental design for a wearable device, as shown and described.

DESCRIPTION

FIG. 1 is a perspective view of a wearable device showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines that are immediately adjacent to the areas included in the claim, and define unshaded regions, represent the bounds of the claim. All other broken lines, including the display rectangle on the top, the band, and the features within broken line boundaries show environment. The broken lines form no part of the claimed design. The portions of the bottom surface that are obscured by the band form no part of the claimed design.

The portions of the bottom surface that are obscured by the band form no part of the claimed design.
